UNITED STATES PATENT OFFICE.

FLOYD FREEMAN, OF NEWARK, OHIO.

CONVEYER.

1,169,948.

Specification of Letters Patent. Patented Feb. 1, 1916.

Application filed June 9, 1914. Serial No. 844,094.

To all whom it may concern:

Be it known that I, FLOYD FREEMAN, a citizen of the United States, residing at Newark, in the county of Licking and State of Ohio, have invented certain new and useful Improvements in Conveyers, of which the following is a specification, reference being had to the accompanying drawings.

This invention relates to certain improvements in conveyers and has relation more particularly to a device of this general character especially designed and adapted for use in connection with glass ware, such as bottles or the like; and an object of the invention is to provide a conveyer of this general character having novel and improved means whereby the bottles or the like after being blown are mechanically carried and deposited in a leer or tempering furnace or other point of discharge.

It is also an object of my invention to provide a novel and improved device of this general character wherein the articles carried thereby are ejected or discharged therefrom in an automatic manner whereby the device may be operated at a comparatively great speed.

It is also an object of my invention to provide a novel and improved conveyer of this general character which may be readily transported from one locality to another in order that it may be employed in connection with different furnaces or points of discharge.

The invention consists in the details of construction and in the combination and arrangement of the several parts of my improved conveyer whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in top plan of a conveyer constructed in accordance with an embodiment of my invention; Fig. 2 is a side elevational view of the device as disclosed in Fig. 1; Fig. 3 is an enlarged sectional view taken substantially on the line 3—3 of Fig. 2; Fig. 4 is a sectional view

taken substantially on the line 4—4 of Fig. 3; Fig. 5 is an enlarged sectional view taken substantially on the line 5—5 of Fig. 2; Fig. 6 is an enlarged sectional view taken substantially on the line 6—6 of Fig. 2; and Fig. 7 is an edge elevational view, detached, of a blade comprised in my device as herein disclosed.

As disclosed in the accompanying drawings, 1 denotes a base member having operatively engaged therewith the supporting wheels 2 whereby the device may be transported from one locality to another with convenience and facility. Supported by the base member 1 is the pedestal or standard 3 capable of vertical adjustment, in a manner which is thought to be self-evident, under the influence of the hand wheel 4. Suitably secured to the upper extremity of the pedestal or standard 3 is the table 5, herein disclosed as substantially square in top plan and having secured thereto at a predetermined distance thereabove through the medium of the supports 6, the stationary conveyer floor 7 herein disclosed as substantially U-shaped in cross section, and of a predetermined length. The forward extremity of the conveyer floor 7 overlies the marginal portion of the circular table or platform 8 loosely mounted on the vertical shaft 9^a and adapted to rotate therearound, in a manner to be hereinafter more particularly referred to.

Operatively supported by the table or platform 8 at a predetermined distance thereabove by the supporting bracket 9 is the swing conveyer floor 10, the major portion of which being substantially U-shaped in cross section and occupying the same horizontal plane as the conveyer floor 7, hereinbefore referred to. The conveyer floor 10 is of predetermined length and is adapted to project within a leer or tempering furnace and is provided with a depending block or member 11 adapted to engage the anti-friction members 12, herein disclosed as conventional spherical bodies, carried by the arcuate track 14 supported in operative position by the brace members 15 projecting forwardly from the table 5.

For properly moving the articles such as blown bottles, along the conveyer floor 7, a sprocket wheel 16 is fixed to the upper extremity of the vertical shaft 17 mounted in the bearing 18 secured to one of the vertical walls of the floor 7 adjacent the outer ex-

tremity thereof and around the sprocket 16 is disposed an endless chain 19 which is also disposed around a second sprocket 20 fixed to the vertical shaft 21 projecting upwardly 5 from the table or platform 5, the lower extremity of said shaft 21 being mounted in the bearing 22 while the upper extremity thereof is mounted in the bearing arm 23 projecting forwardly from the adjacent extremity 10 of the conveyer floor 7.

Interposed between the stretches of the chain 19 and operatively engaged therewith at a point intermediate the sprockets 16 and 20 is a third sprocket 24 fixed to the vertically disposed shaft 25 rotatably supported by the bearing 26 carried by a vertical wall of the conveyer floor 7 and having its lower extremity operatively engaged, as at 27, with the horizontally disposed shaft 28 supported 20 by the bearings 29 mounted upon the table or platform 5.

As herein disclosed, the shaft 28 has affixed thereto a sprocket 30 around which is disposed a chain 31 which is also directed around a sprocket 32 fixed to the horizontally disposed shaft 33 mounted in the bearings 34 and positioned at the marginal portion of the platform opposite to that occupied by the shaft 28. The shaft 33 is also provided 30 with a sprocket 35 around which is disposed a drive chain 36 operatively engaged with the motor M supported by the table 5 and which may be of any type desired. The shaft 33 has also affixed thereto a beveled 35 pinion 37 in mesh with a similar pinion 38 fixed to the horizontally disposed shaft 39 arranged at right angles to the shaft 33 and provided with a second beveled pinion 40 interposed between and in mesh with the 40 spaced beveled gears 41 loosely mounted on the horizontal shaft 42 disposed in parallelism with the shafts 28 and 33, hereinbefore referred to, and projecting beyond one extremity of the table 5, said projected extremity being provided, as herein disclosed, with a hand wheel 43 whereby said shaft 45 may be manually rotated when the requirements of practice may necessitate. The shaft 42 is also operatively supported by 50 the bearings 44 secured to the table or platform 5.

Keyed upon the shaft 42 but capable of movement longitudinally thereof and positioned between the gears 41 is a clutch member 45 adapted to coact with the opposed clutch faces 46 of the gears 41 whereby said shaft 42 may be reversely rotated and, as herein set forth, the clutch member 45 has coacting therewith in a conventional way the 60 yoke 47 mounted for rocking movement about a vertical axis 48 and provided with a lateral extension 49 overlying the marginal portion of the table or platform 8 and positioned between the upstanding projections 65 50 of said table or platform 8 whereby it

will be perceived that automatic means is afforded for reversing the rotation of the shaft 42.

As particularly disclosed in Figs. 3 and 4, the shaft 42 is provided with a worm gear 51 in mesh with the correspondingly toothed periphery 52 of the table or platform 8 whereby it will be perceived that the conveyer floor 10 will be caused to have transverse recurrent movement, so that the ware 75 may be deposited in transverse rows within the leer or tempering furnace. Coacting with the conveyer floor 10 is the endless conveyer chain 53 disposed around an idler roller 54 positioned at the outer extremity 80 of said floor 10 adjacent one vertical face thereof and around and operatively engaged with a sprocket 55 fixed to the shaft 21, hereinbefore referred to, and each of said chains 19 and 53 has operatively engaged with certain of the links thereof the blades 56 which overlie the floors or beds 7 and 10 and are adapted to engage the bottles or other articles adapted to be moved longitudinally of said beds or floors 7 and 10, and, as is particularly illustrated in Fig. 7, it is to be observed that the contacting face of each of the blades 56 is provided with a lining 57 of asbestos or the like, to protect the ware from checking. Secured to 95 a vertical face of the conveyer floor or bed 10 adjacent the inner extremity thereof is a bearing 58 in which is rotatively mounted the vertically disposed shaft 59 having secured to the lower extremity thereof a 100 sprocket wheel 60 to which is eccentrically connected, as at 61, an extremity of an ejector rod 62 underlying the bed or floor 10 and adapted to engage the bottles or other articles as discharged from the outer extremities of said bed or floor 10 and to eject the same a distance sufficient to permit an unobstructed passage of the blades 56, whereby it will be perceived that my improved conveyer may be operated at 110 a comparatively great speed and whereby the possibility of congestion or other obstruction to the operation of the device is reduced to a minimum. As herein embodied, axial rotation is imparted to the 115 sprocket 60 under the influence of the sprocket chain 63 disposed therearound and around the upper member 64 of the double sprocket 65 and disposed around the lower member 66 of said double sprocket is the 120 chain 67 also directed around a sprocket 68 fixed to the shaft 25, hereinbefore referred to.

From the foregoing description, it is thought to be obvious that a conveyer constructed in accordance with my invention 125 is of an extremely simple and comparatively inexpensive nature and is particularly well adapted for use by reason of the convenience and facility with which it may be assembled, and it will also be obvious that my inven- 130

tion is susceptible of some change and modification without material departure from the principles and spirit thereof and for this reason I do not wish to be understood as 5 limiting myself to the precise arrangement and formation of the several parts herein shown in carrying out my invention in practice.

I claim:

- 10 1. A device of the character described comprising a vertically adjustable table, a stationary bed carried thereby, a swinging conveyer bed carried by the table and co-acting with the stationary bed, and a supporting frame carried by the table upon which the swinging conveyer bed rests intermediate its length.
- 15 2. A device of the character described comprising a platform, a conveyer bed supported thereby and capable of swinging movement, an ejector member carried by the conveyer bed and extending to the discharge end of the bed, means carried by the bed for imparting reciprocatory movement to the ejector member, and means carried by the platform for operating said last named means.
- 20 3. A device of the character described

comprising a platform capable of vertical adjustment, a conveyer bed supported thereby and capable of swinging movement, an ejector member carried by the conveyer bed and extending to the discharge end of the bed, means carried by the bed for imparting reciprocatory movement to the ejector member, and means carried by the platform for operating said last named means.

4. A device of the character described comprising a platform, a stationary bed carried thereby, a swinging conveyer bed carried by the platform and coacting with the stationary bed, a supporting frame carried by the platform upon which the swinging bed rests intermediate its length, and anti-friction members carried by the upper surface of the supporting frame and directly engageable with the swinging conveyer bed.

In testimony whereof I hereunto affix my 50 signature in the presence of two witnesses.

FLOYD FREEMAN.
